UNITED STATES PATENT OFFICE.

ALBERT R. PRITCHARD, OF ROCHESTER, NEW YORK.

DESIGN FOR A HANDLE-STRIP FOR VESSELS.

SPECIFICATION forming part of Design No. 28,324, dated March 1, 1898.

Application filed January 7, 1898. Serial No. 665,982. Term of patent 7 years.

To all whom it may concern:

Be it known that I, ALBERT R. PRITCHARD, a citizen of the United States, and a resident of Rochester, in the county of Monroe and State of New York, have invented and produced a new and original Design for a Handle-Strip for Vessels, of which the following is a specification.

My invention consists in the design shown in the accompanying drawings, in which—

Figure 1 is a perspective view of a handle-strip embodying said design, and Fig. 2 is a cross-section on the line 2 2 of Fig. 1.

As shown in the drawings, the leading feature of the design consists in the form and contour of the handle-strip shown in said drawings, which has the flat middle portion

A provided with incurved edge portions *a a*, which are turned down in the same direction from the edges of the middle portion A and are inclined toward each other. From the ends of the middle portion A there extend two other portions B B, each of which is flat and is bent at substantially a right angle to said middle portion. The extremity of each of said portions B has an outward inclination, forming the end pieces *b*.

What I claim is—

The design for a handle-strip for vessels, substantially as shown and described.

ALBERT R. PRITCHARD.
